UNITED STATES PATENT OFFICE.

JOHN HORMBY, OF SPRINGFIELD, MASSACHUSETTS.

TURBINE.

No. 927,535.

Specification of Letters Patent.

Patented July 13, 1909.

Application filed June 19, 1908. Serial No. 439,286.

To all whom it may concern:

Be it known that I, JOHN HORMBY, a citizen of the United States, and a resident of Springfield, in the county of Hampden and 5 State of Massachusetts, have invented certain new and useful Improvements in Turbine-Motors, of which the following is a specification.

My invention relates to motors of the turbine type and its novelty consists in the construction and adaptation of the parts as will be more fully hereinafter pointed out.

In a co-pending application for Letters Patent of the United States, Serial No. 15 439,285 filed by me on the 19th day of June, 1908, I have described a peculiar form of jet propelled vane or bucket which I call for the sake of identification a "demi-vane" and which in brief is made integral with the disk 20 on which it is mounted and comprises a crescent shaped body with cylindrical surfaces oblique to its supporting disk and to the shaft on which it is rotated. The subject matter of this invention is a result of the further development or carrying forward of the inventive ideas described in that application. Necessarily in the description which follows I must repeat something of the descriptive matter of that application.

30 In the drawings, Figure 1 is a miniature front elevation of a double turbine embodying my invention; Fig. 2 is a central section and partial side elevation of the casing and reversing mechanism; Fig. 3 is a side elevation of polyphase motor illustrating the repeated use of the internally expanded stream and showing the parts to the right of the plane 3—3 in Fig. 4, and Fig. 4 is a central section through the parts shown in Fig. 3.

40 In the drawings, 11, 12 and 13 are disks firmly secured to a shaft 10 in any suitable manner, as for instance by means of hubs 110 and 130. The disks 11 and 13 are imperforate on their outer surfaces 200 and each 45 have inwardly projecting rims provided with the demi-vanes referred to. The intermediate disk 12 has a central web and two outwardly projecting rims each provided with demi-vanes. As described in the patent application above referred to, the demi-vanes on the disks 11 and 13 are staggered with respect to those on the intermediate disk 12.

The double turbine so constructed is mounted in an appropriate casing 20 (see 55 Fig. 2) made of steel or any suitable material, the shaft 10 being adapted to project

through the walls thereof. This casing completely encircles the turbine. It is provided with two jets or nozzles, one 21 leading to the vanes between the disks 11 and 12 60 at the upper part of the turbine, as shown in Figs. 1 and 2 and the other 22, leading to the vanes between the disks 12 and 13 at the lower part of the turbine, as shown in the same figures.

65 25 indicates a steam chest divided by a steam tight partition 250 into an upper compartment 210 from which the nozzle 21 draws its steam, and a lower compartment 220 from which the nozzle 22 draws its 70 steam. Within the partition are two oppositely disposed ports 211 and 221 leading to the compartments 210 and 220 respectively, and each of which communicates with a central inlet conduit 251 controlled by a cylindrical valve 26 provided with a port 260 and operated by means of a handle 261.

75 The operation of the device shown in Fig. 2 is quite obvious. If the handle 261 is turned to admit steam from the conduit 251, 80 port 260 and port 211 into the compartment 210, it will pass through the nozzle 21, impinge against the demi-vanes on the disks 11 and 12 and rotate the turbine and its shaft in the direction of the hands of a watch. If, 85 on the contrary, the handle 261 is turned to admit steam through the ports 260 and 221 into the compartment 220 then the steam will pass into the nozzle 22 and against the demi-vanes on the disks 12 and 13 and will 90 rotate the turbine and its shaft in the opposite direction. Obviously by the partial rotation of the handle the steam can be throttled to control the speed of rotation of the turbine so that with a single handle the turbine motor and its shaft may be operated at 95 any desired speed within the limits of the device and either forward or backward. When the handle is in the position shown in Fig. 2 no steam is admitted to either compartment 100 210 or 220 and the turbine motor is at rest.

I have discovered that when a single circumferential row of demi-vanes is used on each disk and its outer surface 200 is imperforate, the steam after passing through the 105 slits between the demi-vanes, reaches the interior of the device and being still under pressure and seeking an outlet, finds one naturally through the slits between the demi-vanes at points away from the influence of 110 the incoming jet and in so doing imparts some energy to the demi-vanes with which

it contacts. It finally escapes within the casing 20 surrounding the motor and may be discharged through a suitable opening 201 provided for that purpose.

5 Utilizing the discovery above referred to, I have constructed a simple and efficient form of turbine, which is a development of the form shown in Figs. 1 and 2. This new form is shown in Figs. 3 and 4. In these figures 20, as before, is a casing surrounding the motor. It is provided with bearings 2 and 3 adapted to support the shaft 10 which is surrounded by a packing indicated at 4. Secured to the shaft 10 is a vertically placed 10 disk 5 provided with annular recesses 50, each adapted to receive rings 51, 52 and 53, which are secured in place by screws 54 or in any other suitable manner. Each of the rings 51, 52 and 53 correspond to the inwardly projecting rims on the disks 11 and 13 (shown in Figs. 1 and 2) and are each provided with a similar series of demi-vanes, each one of which is made of the crescent shaped members made up of cylindrical surfaces 15 oblique to the vertical and horizontal planes. A space is left between the outer surface of the disk 5 and the casing 20 and discharge ports 6 lead thereto from the interior of the motor. Secured to the casing 20 is a vertically placed fixed disk 7 provided with annular recesses 70, each adapted to receive rings 71 and 72 which are secured in place by screws 74 or in any other suitable manner. Each of the rings 71 and 72 are 20 provided with crescent shaped partitions 75 forming between them crescent shaped channels corresponding in number and position to the spaces between the demi-vanes on the rings 51, 52 and 53. A central recess 73 25 serves as a receptacle for the steam and communicates with the discharge ports 6. The disk 7 is circularly adjustable by means of bolts 77, or in any other manner. An inlet nozzle 8 leads to the periphery of the disk 5 30 and the outer vanes. When the steam is turned on, it impinges against these vanes and rotates the disk 5, and shaft 10. Passing through the channels between the vane surfaces in the ring 51 it enters the series of 35 fixed crescent shaped channels in the ring 71 and thence to the vanes in the ring 52, through this ring and through the fixed channels in the ring 72 to the vanes of the ring 53 and thence to the annular recess 73 40 and the discharge ports 6.

It is not necessary that the number of guide channels in the fixed rings should be the same as the number of passages between the vanes in the rings on each side thereof, 45 but it is a convenient way to make the machine in practice.

What I claim as new is:—

1. A shaft, three turbine disks mounted thereon in series, the outer disks having inwardly projecting demi-vanes and the inner

disk outwardly projecting demi-vanes, the vanes of the two series of opposing disks being arranged to receive the impelling fluid in opposite directions whereby the shaft is rotated in one direction when the steam is supplied to one series and in an opposite direction when it is supplied to the other series. 70

2. A shaft, turbine disks mounted thereon in series and provided with demi-vanes extending toward one another, the adjacent 75 vanes of two of said disks being adapted to receive the steam in the same direction.

3. A shaft, turbine disks mounted thereon in series and provided with demi-vanes, the vanes of two adjacent disks being adapted to 80 receive the steam in the same direction, and the vanes of the next pair of adjacent disks being adapted to receive the steam in the opposite direction.

4. A double turbine motor comprising a 85 shaft, and turbine disks mounted thereon in series and provided with vanes, the vanes of two adjacent disks being adapted to receive the steam in the same direction, and the vanes of other adjacent disks being adapted 90 to receive the steam in the opposite direction, in combination with means for supplying steam alternately at such points, substantially as described.

5. A double turbine motor comprising a 95 shaft, and turbine disks mounted thereon in series and provided with vanes extending toward and adjacent one another, the adjacent vanes of the pairs of said disks in the series being adapted to receive the steam in the 100 same direction, to propel said shaft in opposite directions, in combination with means for supplying steam alternately between said pairs of disks, substantially as described.

6. A double turbine motor comprising a 105 shaft, and turbine disks mounted thereon in series and provided with vanes, the vanes of two adjacent disks being adapted to receive the steam in the same direction, and the vanes of other adjacent disks being adapted 110 to receive the steam in the opposite direction, in combination with means for supplying steam alternately at such different points, and for throttling the supply, substantially as described. 115

7. A double turbine motor comprising a shaft, and turbine disks mounted thereon in series and provided with vanes extending toward and adjacent one another, the adjacent vanes of the pairs of said disks in the series 120 being adapted to receive the steam in the same direction, to propel said shaft in opposite directions, in combination with means for supplying steam alternately between said pairs of disks and for throttling the supply, 125 comprising a single rotary valve, substantially as described.

8. A double turbine motor comprising a shaft, turbine disks mounted thereon in series and provided with vanes, the vanes of 130

two adjacent disks being adapted to receive the steam in the same direction, and the vanes of other adjacent disks being adapted to receive the steam in the opposite direction, a casing for said disks, nozzles leading from said casing between different pairs of disks, a steam supply conduit, and means for turning the steam from said conduit into any one of said nozzles, substantially as described.

10. 9. A double turbine motor comprising a shaft, turbine disks mounted thereon in series and provided with vanes extending toward and adjacent one another, the adjacent vanes of the pairs of said disks being adapted to receive steam in the same direction, to propel the said shaft in opposite directions, a casing for said disks, nozzles leading from said casing, between different pairs of said disks, a steam supply conduit, and means for turn-

ing the steam from said conduit into any one 20 of said nozzles, and throttling it, substantially as described.

10. A turbine comprising opposing disks, circular series of crescent shaped demi-vanes extending inwardly from said disks at an angle thereto, and a propelling jet directing steam between said disks and against the adjacent vanes to pass therebetween and between the vanes away from the influence of said jet.

Witness my hand this 17th day of June, 1908, at the city of New York, in the county and State of New York.

JOHN HORMBY.
